Primary Examiner — George A Bugg*Assistant Examiner* — Jessica A Junkins(74) *Attorney, Agent, or Firm* — Michael A. Catania(57) **CLAIM**

The ornamental design for a pouch, as shown and described.

DESCRIPTION

FIG. 1 is a front perspective view of the pouch claimed herein;

FIG. 2 is a front elevation view thereof;

FIG. 3 is a rear elevation view thereof;

FIG. 4 is a side elevation view thereof;

FIG. 5 is a side elevation view thereof;

FIG. 6 is a top plan view thereof; and,

FIG. 7 is a bottom plan view thereof.

The broken line showing of portions of the pouch is included for the purpose of illustrating unclaimed subject matter and forms no part of the claimed design.

1 Claim, 5 Drawing Sheets(56)
